DESIGN FOR A SPECTACLE FRAME OR SIMILAR ARTICLE

Isidor Fishberger, New York, N. Y., assignor of one-half to Emanuel Pappert, Flushing, N. Y.

Application May 20, 1942, Serial No. 106,958

Term of patent 3½ years

To all whom it may concern:

Be it known that I, Isidor Fishberger, a citizen of the United States and a resident of the county of Bronx, city and State of New York, have invented a new, original, and ornamental Design for a Spectacle Frame or Similar Article, of which the following is a specification, reference being had to the accompanying drawing, forming a part thereof in which

tacle frame or similar article showing my new design; and

Fig. 2 is a top plan view thereof.

The essential features of my design are shown in full lines.

I claim:

The ornamental design for a spectacle frame or similar article, as shown and described.

ISIDOR FISHBERGER.
